UNITED STATES PATENT OFFICE.

RAYMOND ROBERT MACHLETT, OF NEW YORK, N. Y., ASSIGNOR TO RAINBOW LIGHT, INC., A CORPORATION OF NEW YORK.

NEON TUBE.

Application filed October 20, 1926. Serial No. 142,839.

My invention relates to various new and useful improvements in luminous tubes, particularly those in which a conducting atmosphere of neon is used. I prefer to make use of neon owing to its brilliant and attractive color when rendered luminous by a high tension discharge, but the invention can also be utilized with other monatomic inert gases of the so-called noble group, including argon, helium, krypton and xenon, all of which have their characteristic spectra. These latter gases however do not possess the extremely favorable characteristics of neon.

In the manufacture of neon tubes, prior to my invention, it was considered necessary to make use of relatively large electrodes of the order of fifteen or more square decimeters per ampere of current, in order to minimize the phenomenon of electrical evaporation observed by Sir Wm. Crookes and referred to for example by E. C. C. Baly "The Spectra of Neon, Krypton and Xenon" Philosophical Transactions, Royal Society, 1903, A. 202, page 185. As Baly points out in this article, neon is absorbed by the electrode metal deposited upon the walls of the tubes, thus depleting the atmosphere and shortening the life of the tube.

Even when neon tubes are made with electrodes having an area of fifteen or more square decimeters per ampere of current and the negative glow does not cover the entire electrode surface, there is a very substantial energy loss due to the sharp fall of potential between the electrodes and the luminous column.

With my improved neon tube, as will be hereinafter described, I am enabled to make use of electrodes of as small an area, as .9 square decimeters per ampere and to operate the tube with such electrodes in an entirely efficient and useful way, and without undue heating or sputtering of the electrodes. At the same time, I improved the efficiency, because with the tube of my invention the capacity reactance is materially reduced, while the ohmic resistance is increased.

In explanation of the statement just made, I point out that when voltage is applied to a neon or other gas discharge tube, this voltage is utilized to overcome the usual components of impedance offered by a circuit to the flow of alternating current. By actual test it has been found that the total voltage drop is due to two components of impedance—one due to

capacity which results mainly from the electrical conditions at the electrodes where a very large percentage of positive ions are accumulated as each electrode functions as a cathode; and the other due to pure ohmic resistance in the luminous column itself where the negative and positive ions exist in approximately equal proportions. The luminous effect is a function of the ohmic resistance and any increase in this impedance factor results in greater luminous efficiency.

Specifically I have discovered that if a luminous tube filled with neon or other monatomic gas under reduced pressure, is provided with interior electrodes and if a mirror of an electro-positive alkali metal, such as metallic caesium is deposited upon the tube walls somewhat in advance of each electrode, very remarkable and unexpected results are secured. With such a tube, the electrodes do not heat in operation even when of very small area and therefore the vaporization effect is very substantially reduced. Furthermore the distribution of energy is so altered as to result in an increase of ohmic resistance in the gaseous column and thus a more effective application of energy for illuminating purposes. Such an increase of efficiency has actually been measured in terms of wattage and may amount to as much as 20% as compared to that of a standard neon tube without caesium and having electrodes of large area.

In order that the invention may be better understood, attention is directed to the accompanying drawing in which a tube is shown embodying my present invention and in connection with which I will describe the use of metallic caesium as the electro-positive alkali metal.

The main body of the tube 1, is made of glass of suitable dimensions and is generally bent into the form of a symbol or letter for advertising purposes. Owing to the fact that the improved tube lends itself so favorably to use with currents of great magnitude, it may be and has been effectively utilized as a beacon light for aerial navigation. For such use, tubes of from three to five meters in length have been operated with currents of 5 and more amperes through the tube, thus giving a concentrated source of illumination of intense brilliancy. The ends of the tube are enlarged at 2, as shown, and within each enlargement is a stem, 3, formed integral

therewith, upon which stem is mounted the electrode, 4, generally a thin copper shell. Current is conveyed to each electrode by the usual conductor 5. The maximum area of 5 the electrode is practically immaterial, but in practice I have made them with an area of only .9 square decimeters per ampere or even less. Their size depends largely upon 10 convenience and ease of construction from a mechanical point of view. The enlarged ends of the tube as shown, are preferably conical or pear shaped, providing a chamber of substantial size surrounding each electrode. During the final stages of exhaustion of the 15 tube and just prior to the admission of the neon gas in the tube, a mirror of pure metallic cæsium 6 is distilled into the chamber surrounding the electrode and manipulated by heating so as to deposit it in the general position 20 illustrated.

The formation of the tube may be carried out in any suitable way, but I prefer to make use of the purifying method disclosed in my patent granted February 22, 1927, No. 25 1,618,767, wherein the tube is subjected to a baking operation at a high temperature during its exhaustion, followed by a special purification process involving the use of a vapor of an alkali metal. In my said application I 30 suggest particularly the use of metallic potassium as the alkali metal, the vapor of which is to be used in effecting the final stages of purification of the tube, but I find that cesium can also be employed for the purpose and 35 therefore I utilize the vapor of cæsium in the same way as the vapor of metallic potassium, as described in said application. The cæsium is thus used as a matter of convenience, since it is at hand.

40 After the tube has been thus thoroughly purified by the vapors of metallic cæsium, the temperature of the tube is reduced as disclosed in said application, after which, when the tube has cooled, the cæsium mirror is 45 formed adjacent to the electrodes, as I have

already described. Such a process of purification is extremely effective, and when the neon is introduced at a pressure of about 8 millimeters of mercury, the most desirable results will be secured.

As I have indicated, the presence of the cæsium mirror in the neighborhood of the electrodes, permits me to operate effectively with electrodes of extremely small superficial area in proportion to the current employed. 50 Furthermore, the presence of this cæsium mirror has the unexpected effect of substantially changing the energy distribution in the tube in such a manner that it now takes place chiefly in the gas and to a reduced extent at 55 the electrodes.

Having now described my invention, what I claim as new therein and I desire to secure by patent, is as follows:

1. A luminous tube containing a conducting atmosphere of a monatomic inert gas, electrodes therein having an area less than one square decimeter per ampere and a deposited mirror of an electro-positive metal on the walls of the tube adjacent to the cathode, as 60 set forth.

2. A luminous tube containing a conducting atmosphere of a monatomic inert gas, electrodes therein having an area less than one square decimeter per ampere and a deposited 75 mirror of metallic cæsium on the walls of the tube adjacent to the cathode, as set forth.

3. A luminous tube containing an atmosphere of neon gas, electrodes therein having an area of less than one square decimeter per 80 ampere and a deposited mirror of an electro-positive metal on the walls of the tube adjacent to the cathode, as set forth.

4. A luminous tube containing an atmosphere of neon gas, electrodes therein having an area of less than one square decimeter per 85 ampere and a deposited mirror of metallic cæsium on the walls of the tube adjacent to the cathode, as set forth.

RAYMOND ROBERT MACHLETT.
